MULTIPLE ELECTRICAL CONNECTOR

Leon Gilbert, Stamford, Conn., assignor to Continental Connector Corporation, Long Island City, N. Y., a corporation of New York

Application September 8, 1955, Serial No. 533,114

11 Claims. (Cl. 339—176)

This invention relates to improvements in multiple electrical connectors, particularly of the miniature type.

The prime object of my present invention centers about the provision of an improved electrical connector comprising a jack or receptacle having multiple miniature contact elements which jack or receptacle is adapted or designed to receive printed circuit cards or plugs provided with mating multiple circuit contacts, the improvement being directed to the more efficient construction of the contact elements for the more effective solution of circuit contact problems that occur in this type of equipment.

In multiple electrical connectors of this referred to type, a large group of miniature contact elements, ranging from ten to twenty or more, are mounted in closely spaced relation in a single receptacle designed to receive a printed circuit board or card or similar plug containing a correspondingly large group of closely spaced circuit elements adapted for mating contact with said contact elements. The multiple connector and particularly the multiple contact elements thereof must be so designed as to assure the effective electrical engagement of the contacts and the closing of all of the involved circuits. To effectuate this in multiple electrical connectors of prior makes, the contact elements of the receptacles (or of the plugs, where the latter also included similar contact elements) were made to comprise leaf springs made of strip spring stock, the contact portion of which was bowed or bent so as to be in the path of movement of the plug contact to assure engagement therebetween. Such engagement while effectively obtained, yields, however, but a line or small area contact and therefore an inadequate electrical engagement between the connector elements.

In the improved multiple connector of the present invention, the contact elements, although made of strip spring stock, are constructed to act as compression springs, as distinguished from leaf springs, and are constructed in the form of a bellows, the outermost or contact branch of which, preferably straight or linear in shape, is adapted to make contact over its full face or area, as distinguished from a line contact, with the circuit element or contact of the printed circuit card or other plug. The bellows action, moreover, makes the face of the contact element follow the printed circuit, preventing circuit discontinuities under severe vibration and printed circuit board misalignment due to tolerance buildup on the equipment in which this type of connector is used. Where these compression spring bellows contacts are arranged as pairs on oppositely facing sides of the connector, the further result is achieved that the printed circuit card or plug assembly is securely held resiliently in the receptacle connector by the oppositely acting compression action of the contact pairs.

To the accomplishment of the foregoing object and such other objects as may hereinafter appear, my invention relates to the multiple electrical connector as sought to be defined in the appended claims and described in

2

the following specification taken together with the accompanying drawings, in which:

Fig. 1 is a rear perspective view of the multiple electrical connector of the present invention shown in combination with a printed circuit plug assembly, with parts shown in cross-section;

Fig. 2 is a front perspective view of the multiple electrical connector;

Fig. 3 is a view shown to an enlarged scale taken in cross-section in a plane corresponding to the cross-sectional part of Fig. 1 of the drawings;

Fig. 4 is a view similar to Fig. 3 and showing the manner in which contact is made between the contact elements of the electrical connector and the circuit contacts of a printed circuit card or board, the said printed circuit card having a relatively small width or thickness;

Fig. 5 is a view corresponding to Fig. 4 of the drawings and showing the manner in which contact is made with a printed circuit card or board having a width or thickness greater than that illustrated in Fig. 4; and

Fig. 6 is a similar cross-sectional view of an electrical connector embodying a modification of the structure of the present invention.

Referring now more in detail to the drawings and having reference first to Figs. 1 to 3 thereof, the multiple electrical connector comprises a jack assembly generally designated as J adapted to receive a printed circuit plug assembly P or any like plug assembly, the said jack assembly being provided with a plurality or series of miniature contact elements c, c, the printed circuit plug assembly P being provided with a plurality of circuit elements or strips c', c' the termini of which define contact elements for mating cooperation with the contact elements of the jack assembly J.

The jack assembly J comprises more specifically a receptacle 10 made of a single molded piece of insulation formed with a central longitudinal trough 12 for receiving the plug assembly P, the said trough being defined by two oppositely facing walls 14 and 16, at least one and preferably both of which walls are formed with a plurality of pockets 18, 18 spaced along the trough corresponding in number to the number of contact elements c, each contact element being located and partially housed by a pocket. The walls 14 and 16 form the inside walls of said pocket, the side walls of said pocket being defined by ribs 20, 20 directed inwardly of said walls. The receptacle 10 is also formed at its top with shoulders 22, 22 extending the length of the trough and with a boss or protruberance 24 at its bottom also extending the length of the trough for purposes that will appear hereinafter. The receptacle 10 may also be formed with terminal lug portions 26, 26 for the reception of attaching elements.

Each of the contact elements c, c comprises a bellows shaped spring unit made from strip spring stock such as spring tempered, Phosphor bronze (which may be gold plated over silver for obtaining low contact resistance) having three branches, an innermost branch 28 being lodged against the inside wall such as the wall 14 or the wall 16 of a pocket 18, an outermost branch 30 defining the contact which is engageable by a mating contact of the plug assembly and an intermediate branch 32 forming a spring connection between the other two branches. The lower end of the innermost branch 28 of each bellows shaped contact c is anchored as at 34 to the body of the receptacle 10 and the receptacle protruding ends 36 thereof define terminal ends to which conductors may be connected as by soldering. The outermost branch 30 of the contact c terminates at its upper end in a hook portion 38 which is engaged by and over the shoulder wall 22, the end of the hook portion having a limited freedom of movement in a recess 40 formed between said shoulder

and the outer walls 42 of the receptacle. The wall shoulder 22 forms a stop for limiting the outward movement of the top of the contact elements *c* and the boss 24 forms a stop for limiting the outward movement of the bottom of the contact elements *c*. The action of the bellows contacts of this multiple connector may be explained by reference to Figs. 3, 4 and 5 of the drawings. It is preferred, whether a single line of contacts is provided for (Fig. 6) or whether a double line of contacts is embodied in the instrument, to have a double line of contact elements *c*, *c* arranged in oppositely facing pairs as clearly depicted in Figs. 3, 4 and 5 of the drawings, the pockets 18, 18 in the receptacle being therefore also arranged in registering pairs in the oppositely facing walls 14 and 16. Fig. 3 depicts the position assumed by the contact elements *c*, *c* in the absence of a plug assembly, the contact branches 30, 30 being shown to protrude a substantial distance beyond the ribs 20, 20. It will be noted that the branch 30 of the contact element *c* is straight or linear in form or shape, as distinguished from being bowed or bent along its length.

Fig. 4 illustrates the action that takes place upon the reception of a printed circuit card *P* of a thickness which is relatively narrow and substantially less than the distance between the facing ribs 20, 20. Upon entry of the printed circuit card *P* into the trough of the receptacle, engagement between a circuit element *c'* is made at once with the top of the outermost branch 30 of the contact element *c*, this branch pivoting about the lower bend *b* of the contact element. As the plug *P* is moved further into the trough this action continues together with a pivoting of the intermediate branch 32 about the upper bend *b'* of the contact element. As the plug *P* is forced into its "home" position the contact *c*, in its action as a bellows, is compressed, the contact also acting as a whole as a compression spring. The result is that the electrical engagement branch 30 of the contact element *c*, linear in shape as aforesaid, makes contact over its full face or area as distinguished from a line contact, with the circuit element *c'* of the printed circuit plug. With the compression spring bellows contacts *c*, *c* arranged as pairs on oppositely facing sides of the connector, the further result is achieved that the branch circuit card or plug assembly is securely held resiliently in the receptacle connector by the oppositely acting compression action of the contact element pairs. The bellows action, moreover, makes the face of the contact branch 30 follow the printed circuit, preventing circuit discontinuities under severe vibration and printed circuit board misalignment due to tolerance build-up on the equipment in which this type of connector is used.

Fig. 5 depicts the action that takes place upon the reception of a printed circuit card *P'* which is relatively wider than the thickness of the printed card *P* of Fig. 4. For example, in a commercial structure of the connector the thickness or width of the printed circuit card *P* may be .061 inch whereas that of the printed circuit card *P'* may be as much as ten one-thousandths of an inch greater, namely, .071 inch. The actions that take place in Fig. 5 of the drawings are otherwise the same as those described for Fig. 4 of the drawings with the exception of course that the contact elements *c*, *c* are subjected to a greater compression. Figs. 4 and 5 taken together illustrate the ability of the electrical connector to take or receive printed circuit cards or boards of substantially different widths or thicknesses, the contact elements functioning in all cases effectively for obtaining a full face or area contact with the plug assembly securely held resiliently in the receptacle connector by the compression spring action of the contact element pairs.

Fig. 6 illustrates a modified form of the electrical connector of the present invention; and in this modification the oppositely facing contacts *c*², *c*², instead of being made in the form of two sets of contact elements is constructed to form a single set of contact elements. To

this end the oppositely facing pairs of contact elements *c*², *c*² are joined in a medial connecting branch 44. Otherwise the parts of the receptacle are the same as those of the form of the invention described in Figs. 1 to 5, similar parts being indicated by primed reference characters.

The manner of making, the mode of operating, as well as the uses and advantages of the multiple miniature electrical connector of the present invention will in the main be fully apparent from the above detailed description thereof. It will be further apparent that many changes may be made in the electrical connector without departing from the spirit of the invention defined in the following claims.

I claim:

15. A multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said contact elements at points remote from the open top of said trough, and limiting the movement of said outermost contact element sections laterally away from said innermost contact element sections.
20. The multiple electrical connector of claim 1, in which said spring unit comprises three sections, to wit, said innermost and outermost sections and an intermediate section forming a spring connection between the upper end of said innermost section and the lower end of said outermost section.
25. The multiple electrical connector of claim 1, in which said spring unit comprises three sections, to wit, said innermost and outermost sections and an intermediate section forming a spring connection between the upper end of said innermost section and the lower end of said outermost section.
30. The multiple electrical connector of claim 1, in which said spring unit comprises three sections, to wit, said innermost and outermost sections and an intermediate section forming a spring connection between the upper end of said innermost section and the lower end of said outermost section.
35. The multiple electrical connector of claim 1, in which said spring unit comprises three sections, to wit, said innermost and outermost sections and an intermediate section forming a spring connection between the upper end of said innermost section and the lower end of said outermost section.
40. The multiple electrical connector of claim 1, in which said spring unit comprises three sections, to wit, said innermost and outermost sections and an intermediate section forming a spring connection between the upper end of said innermost section and the lower end of said outermost section.
45. The multiple electrical connector of claim 1, in which said spring unit comprises three sections, to wit, said innermost and outermost sections and an intermediate section forming a spring connection between the upper end of said innermost section and the lower end of said outermost section.
50. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said
55. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said
60. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said
65. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said
70. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said
75. The multiple electrical connector comprising a jack assembly adapted to receive a printed circuit plug or like assembly, said jack assembly comprising a receptacle, said receptacle having an open-topped trough for receiving the plug assembly defined by two oppositely facing walls, contact elements spaced from one another along said trough, said contact elements each being formed from a strip of conductive material of substantially uniform thickness and resilient along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact of the plug assembly and comprising a substantially straight length of said strip the free terminal portion of which lies adjacent said open trough top, the said bellows-shaped spring unit being contact active as a compression spring, whereby a full surface engagement is obtained between said contact section of the unit and the mating contact of the plug assembly, and an element extending into said trough, engageable with the outermost of said sections of said

contact elements at points remote from the open top of said trough, and limiting the movement of said outermost contact element sections laterally away from said innermost contact element sections.

4. The multiple electrical connector of claim 3, in which said spring unit comprises three sections, to wit, said innermost and outermost sections and an intermediate section forming a spring connection between the upper end of said innermost section and the lower end of said outermost section.

5. A multiple electrical connector comprising a jack assembly adapted to receive a printed circuit plug or like assembly the plug portion of which is planar and has flat contact areas, said jack assembly comprising a receptacle, said receptacle having a straight elongated open-topped trough for receiving the plug assembly defined by two oppositely facing walls, contact elements spaced from one another along said trough, said contact elements each being formed from a strip of thin conductive material which is resiliently flexible along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact area of the plug assembly and comprising a length of said strip the free terminal portion of which lies adjacent said open trough top, the surface of said strip length directed toward the interior of said trough being flat, the said bellows-shaped spring unit being contact active as a compression spring, whereby a full surface engagement is obtained between said contact section of the unit and the mating contact area of the plug assembly, and an element extending into said trough, engageable with the outermost of said sections of said contact elements at points remote from the open top of said trough, and limiting the movement of said outermost contact element sections laterally away from said innermost contact element sections.

6. A multiple electrical connector comprising a jack assembly adapted to receive a printed circuit plug or like assembly the plug portion of which is planar and has flat contact areas, said jack assembly comprising a receptacle, said receptacle having a straight, elongated open-topped trough for receiving the plug assembly defined by two oppositely facing walls, at least one of the walls having a plurality of protruding portions spaced along the trough, contact elements located between said protruding portions, said contact elements each being formed from a strip of thin conductive material which is resiliently flexible along substantially its entire length, said strip comprising a plurality of sections connected by integral reverse bends to comprise a bellows-shaped spring unit, the innermost of said sections being lodged against one of said trough walls, anchored at one end to the receptacle at a point remote from the open top of said trough and extending toward said open trough top, the outermost of said sections defining the contact which is engageable by a mating contact area of the plug assembly and comprising a substantially straight length of said strip the terminal portion of which lies adjacent said open trough top, the surface of said strip length directed inwardly with respect to said trough being flat, the said bellows-shaped spring unit being contact active as a compression spring, whereby a full surface engagement is obtained between said contact section of the unit and the mating contact area of the plug assembly, and an element extending into said trough, engageable with the outermost of said sections of said contact elements at points remote from the open top of said trough, and limiting the movement of said outermost contact element sections laterally away from said innermost contact element sections.

7. A multiple electrical connector comprising a jack assembly adapted to receive a printed circuit plug or like assembly the plug portion of which is planar and has flat contact areas, said jack assembly comprising a receptacle, said receptacle having a straight elongated open-topped trough for receiving the plug assembly defined by two oppositely facing walls, at least one of the walls being formed with a plurality of pockets spaced along the trough, contact elements in said pockets, said contact elements each being formed from a strip of thin conductive material which is resiliently flexible along substantially its entire length, said strip comprising a plurality of sections connected by integral reverse bends to comprise a bellows-shaped spring unit, the innermost of said sections being lodged against the inside wall of a pocket, anchored at one end to the receptacle at a point remote from the open top of said trough and extending toward said open trough top, the outermost of said sections defining the contact which is engageable by a mating contact area of the plug assembly and comprising a length of said strip the terminal portion of which lies adjacent said open trough top, the surface of said strip length directed toward the interior of said trough being flat, the depth of said pockets being greater than the combined thicknesses of said sections, the said bellows-shaped spring unit being contact active as a compression spring, whereby a full surface engagement is obtained between said contact section of the unit and the mating contact area of the plug assembly, and an element extending into said trough, engageable with the outermost of said sections of said contact elements at points remote from the open top of said trough, and limiting the movement of said outermost contact element sections laterally away from said innermost contact element sections.

8. A multiple electrical connector comprising a jack assembly adapted to receive a printed circuit plug or like assembly the plug portion of which is planar and has flat contact areas, said jack assembly comprising a receptacle, said receptacle having a straight, elongated open-topped trough for receiving the plug assembly defined by two oppositely facing walls, at least one of the walls being formed with a plurality of pockets spaced along the trough, contact elements located in said pockets, said contact elements each being formed from a strip of thin conductive material which is resiliently flexible along substantially its entire length, said strip comprising a plurality of sections connected by integral reverse bends to comprise a bellows-shaped spring unit, the innermost of said sections being lodged against the inside wall of a pocket, anchored at one end to the receptacle at a point remote from the open top of said trough and extending toward said open trough top, the outermost of said sections defining the contact which is engageable by a mating contact area of the plug assembly and comprising a substantially straight length of said strip the terminal portion of which lies adjacent said open trough top, the surface of said strip length directed inwardly with respect to said trough being flat, the depth of said pockets being greater than the combined thicknesses of said sections, the said bellows-shaped spring unit being contact active as a compression spring, whereby a full surface engagement is obtained between said contact section of the unit and the mating contact area of the plug assembly, and an element extending into said trough, engageable with the outermost of said sections of said contact elements at points remote from the open top of said trough, and limiting the movement of said outermost contact element sections laterally away from said innermost contact element sections.

9. A multiple electrical connector comprising a jack assembly adapted to receive a printed circuit plug or like assembly, said jack assembly comprising a receptacle, said receptacle having an open-topped trough for receiving the plug assembly defined by two oppositely facing

side walls and a bottom wall, at least one of the side walls being formed with a plurality of pockets spaced along the trough, contact elements one located in each pocket, said contact elements each being formed from a strip of conductive material resilient along substantially its entire length, said strip comprising a plurality of sections connected by integral reverse bends to comprise a bellows-shaped spring unit, the innermost of said sections being lodged against the inside wall of a pocket, and supported by said wall along substantially its entire length against movement laterally inwardly of said pocket, said bottom wall having a slot therethrough, said contact element comprising an extension from said innermost section passing through said slot to and beyond the exterior of said receptacle and there defining a terminal end to which an external circuit may be connected, said innermost section being anchored at one end to the receptacle at a point remote from the open top of said trough against movement upwardly or laterally outwardly of said pocket and extending toward said open trough top, the outermost of said sections, spaced outwardly from said inside pocket wall, defining the contact which is engageable by a mating contact of the plug assembly and comprising a substantially straight flat length of said strip the free terminal portion of which lies adjacent said open trough top, the depth of said pockets being greater than the combined thicknesses of said sections, the said bellows-shaped spring unit being contact active as a compression spring, whereby a full surface engagement is obtained between said contact section of the unit and the mating contact of the plug assembly.

10. A multiple electrical connector comprising a jack assembly adapted to receive a printed circuit plug or like assembly, said jack assembly comprising a receptacle, said receptacle having an open-topped trough for receiving the plug assembly defined by two oppositely facing side walls and a bottom wall, contact elements spaced from one another along said trough, said contact elements each being formed from a strip of conductive material resilient along substantially its entire length, said strip comprising a plurality of sections connected by integral reverse bends to comprise a bellows-shaped spring unit, the innermost of said sections being lodged against one of said side walls and supported by said wall along substantially its entire length against movement toward said side wall, said bottom wall having a slot therethrough, said contact element comprising an extension from said innermost section passing through said slot to and beyond the exterior of said receptacle and there defining a terminal end to which an external circuit may be connected, said innermost section being anchored at one end to the receptacle at a point remote from the open top of said trough against movement upwardly or laterally outwardly from said side wall and extending toward said open trough top, the outermost of said sections,

spaced outwardly from said side wall, defining the contact which is engageable by a mating contact of the plug assembly and comprising a substantially straight flat length of said strip the free terminal portion of which lies adjacent said open trough top, the said bellows-shaped spring unit being contact active as a compression spring, whereby a full surface engagement is obtained between said contact section of the unit and the mating contact of the plug assembly.

- 15 5 11. A multiple electrical connector comprising a jack assembly adapted to receive a printed circuit plug or like assembly, the plug portion of which is planar and has flat contact areas, said jack assembly comprising a receptacle, said receptacle having a straight elongated open-topped trough for receiving the plug assembly defined by two oppositely facing side walls and a bottom wall, contact elements spaced from one another along said trough, said contact elements each being formed from a strip of thin conductive material which is resiliently flexible along substantially its entire length, said strip comprising a plurality of sections connected by integral reverse bends to comprise a bellows-shaped spring unit, the innermost of said sections being lodged against one of said side walls and supported by said wall along substantially its entire length against movement toward said wall, said bottom wall having a slot therethrough, said contact element comprising an extension from said innermost section passing through said slot to and beyond the exterior of said receptacle, and there defining a terminal end to which an external circuit may be connected, said innermost section being anchored at one end to the receptacle at a point remote from the open top of said trough against movement upwardly or laterally outwardly from said side wall and extending toward said open trough top, the outermost of said sections, spaced outwardly from said side wall, defining the contact which is engageable by a mating contact area of the plug assembly and comprising a length of said strip the free terminal portion of which lies adjacent said open trough top, the surface of said strip length directed toward the interior of said trough being flat, the said bellows-shaped spring unit being contact active as a compression spring, whereby a full surface engagement is obtained between said contact section of the unit and the mating contact area of the plug assembly.
